[57] CLAIM

The ornamental design for a humidor, as shown and described.

DESCRIPTION

FIG. 1 is a front perspective view of a humidor, showing my new design;

FIG. 2 is a front elevation view;

FIG. 3 is a side elevation view;

FIG. 4 is a side elevation view;

FIG. 5 is a rear elevation view; and,

FIG. 6 is a top plan view.

For convenience of illustration, the pattern displayed in FIG. 1 is represented in part only to illustrate a uniformly continuous pattern over the surface on which it is shown.
